UNITED STATES PATENT OFFICE

170,083

FIGURE TOY

Benjamin Gelardin, New York, N. Y.

Application February 2, 1953, Serial No. 23,403

Term of patent 7 years

(Cl. D34—15)

To all whom it may concern:

Be it known that I, Benjamin Gelardin, a citizen of the United States, residing at 200 Cabrini Boulevard, New York, New York, have invented a new, original, and ornamental Design for a Figure Toy, of which the following is a specification, reference being had to the accompanying drawing, forming part thereof.

Fig. 1 is a perspective view of a figure toy, showing my new design; and

Fig. 2 is a side elevational view thereof.

I claim:

The ornamental design for a figure toy, as shown.

BENJAMIN GELARDIN.
